REFRIGERATED CABINET

John K. Wagner, deceased, late of Marengo, Iowa by Jeanette A. Wagner, administratrix, Marengo, Iowa, assignor to Amana Refrigeration, Inc., Amana, Iowa, a corporation of Delaware

Filed Sept. 2, 1966, Ser. No. 3,724

Term of patent 14 years

(Cl. D67—3)

FIG. 1

FIG. 4

FIG. 1 is a perspective view of a refrigerated cabinet showing my new design;

FIG. 2 is a vertical sectional view taken along the line 2—2 of FIG. 1;

FIG. 3 is a horizontal sectional view taken along the line 3—3 of FIG. 1; and

FIG. 4 is a fragmentary perspective view of an ornamental portion of one of the doors.

The dominant feature of my design resides in the portions shown in full lines.

I claim:

The ornamental design for a refrigerated cabinet, substantially as shown and described.
